PORTABLE POWER-DRIVEN TOOL

Gilbert B. Larson, Geneva, Ill., assignor to Independent Pneumatic Tool Company, Chicago, Ill., a corporation of Delaware

Application April 20, 1945, Serial No. 589,424

3 Claims. (Cl. 81—54)

1

This invention relates to improvements in valve controlling means for supplying motive fluid to rotary impact and other portable power operated tools.

The principal object and purpose of my invention is to provide a valve control mechanism incorporated in the tool and operable in response to pressing the tool against the work to open the valve or condition it to immediately supply an increased amount of motive fluid to operate the tool motor to pick up the load impressed thereon.

A further object of my invention is to provide a control rod or element for opening the valve and have said element located in or operate through or around the tool motor and the tool spindle.

A further object of my invention is to locate the valve to be operated by the rod either in offset relation thereto or directly in line therewith.

A further object of my invention is to have the rod actuate the valve by the relative movement between the tool and the work engaging fixture at the front of the tool.

A further object of my invention is to provide said valve controlling mechanism in conjunction with the regular starting and stopping valve on the tool whereby the tool may be run idly at a relatively slow speed, and be immediately increased in speed on pressing the tool against the work to handle the load suddenly placed thereon.

The invention consists further in the features of construction and the combination of parts hereinafter described and claimed.

In the accompanying drawings—

Fig. 1 is a longitudinal sectional view of a portable power operated impact tool embodying a valve control of my invention and showing a lever member connecting the control rod with the laterally off-set valve; and

Fig. 2 shows an adaptation of my invention with the valve arranged in direct line with the control rod.

The tool of Fig. 1 has an outer casing 1 containing the tool motor 2 and the impact clutch mechanism 3 as in tools of this character. The outer casing 1 has a side handle 4 provided with a supply passage 5 for conveying compressed air to the tool motor 2 for rotating it. The outer end of the handle 4 has a fitting 6 whereby an air supply hose (not shown) may be connected to the tool. The handle 4 mounts the regular or throttle valve 7 of the tool, said valve being spring biased to closed position, and opened by a trigger block 8 carried by the handle. The valve 7 controls the flow of compressed air from the

2

handle passage 5 to a supply passage 9 provided in the outer casing 1 of the tool. The passage 9 leads to a main inlet port 10 of the porting system for the tool motor 2 and said port 10 is opened and closed by a spring biased valve member 11 in accordance with my invention.

The tool motor 2 is of the rotary type having a rotor 12 having radial blades 13 operating in slots 14. The blades 13 cooperate with a motor cylinder 15 doweled or otherwise fixed against rotation in the tool case and closed at its opposite ends by end plates 16, 17 as shown in Fig. 1. The porting system of the tool follows the usual practice in this art and is such that the tool motor 2 is rotatable in reverse directions, there being a reversing valve (not shown) in the assembly for controlling this.

Located in the forward part of the tool case 1 is the impact clutch mechanism 3 which in the instant showing is of the cam centrifugal type described and claimed in the Louis P. Fosnot application Ser. No. 475,377, filed February 10, 1943, now Patent No. 2,425,793, and assigned to the assignee of the instant application.

This clutch mechanism as shown herein comprises briefly a rotary hammer member 18 revolvably mounted on a shaft 19 splined or otherwise directly secured to the lower trunnion 20 of the rotor at 21. This shaft 19 is axially aligned with the rotor 12 and mounts a driving member 22 having a pair of upper and lower plates 23, 24 keyed respectively to the upper and lower end portions of the shaft 19 as indicated in Fig. 1.

Mounted in a diametric slot 25 in the hammer member 18 is a pair of slidable dogs or impact members 26, 26 through which extend mounting pins 27, 27. There is a pin 27 for each impact element and said pins extend through radial slots 28 in the body of the hammer member 18 and beyond the same into cam slots 29, 29 of generally arcuate shape, in the plates 23, 24, respectively.

Forming a part of and surrounding the clutch mechanism is an anvil member 30 in hollow cylindrical shape and having a pair of axially extending jaws 31, 31 as shown. The openings between the jaws 31 allow the impact elements 26 to move by centrifugal force into the orbital path of the jaws to engage them in the operation of the clutch. In the rotation of the hammer member 18 relatively to the anvil member 30, the impact elements 26 strike against the side edges of the jaws 31 to deliver rotational hammer blows thereto. This occurs when free rotation of the anvil member 30 is arrested by engagement of

the tool with the work. The anvil member 30 has a spindle 32 to journal it in the tool case 1.

The impact elements 26 have impact delivery surfaces on their opposite sides and the jaws 31 have complementary impact receiving surfaces at their opposite sides whereby the clutch mechanism can operate in either direction of rotation of the tool motor. The impact delivering and receiving surfaces above mentioned are substantially straight, the impact elements 26 being 10 in rectangular block-like form.

The spindle 32 is made hollow to receive and drive in the embodiment shown in Fig. 1 the non-circular stem 33 of an adapter fixture 34. The latter extends axially below the spindle and has a flange portion 35 and a non-circular portion 36 below the same. The portion 36 is preferably square in cross-section to mount a nut or bolt head engaging socket member 37. These two parts are held in connected relation by a spring biased detent pin 38 carried by the adapter and snapping into a hole 39 in the socket member 37. The upper stem portion 33 of the adapter is slidably retained in the spindle 32 by the pin and slot connection, the pin being marked 40 and the slot 41. The flange 35 limits the relative sliding movement between the adapter 34 and the spindle 32 when pressing the tool against the work.

In the form of my invention as shown in Fig. 1, the inlet valve 11 is laterally offset with respect to the axis of the rotor 12. The valve 11 is in the form of a sleeve open at both ends and receiving a coiled spring 42 for normally urging the sleeve into the closed position of the valve. The spring 42 seats at its lower end against the upper end plate 16 of the motor assembly and engages at its upper end a shoulder in the sleeve 11 to raise it. The upper end of the sleeve 11 is provided with ports 43, 43 for admitting compressed air through the sleeve when in open position. At this time, the sleeve 11 is depressed with its upper end out of the recess in the top wall 44 of the valve housing and the compressed air may flow into the ports 43 from the main port 10. The housing for the valve 11 is provided with a side port over which the valve 11 has movement and which side port, marked 45, is in constant register with the port 10. A port at the lower end of the valve housing is in communication with the open lower end of the sleeve 11 and is included in the porting system for supplying compressed air to the tool motor.

The sleeve 11 has a stem member 46 which extends upwardly through the top wall 44 of the valve housing and is pressed by the spring 42 against a lever 47 fulcrumed at 48 to the adjacent fixed parts of the tool housing 1 and having an arm portion 49 extending to and bearing on the upper end of a push rod 50. The latter is slidably mounted in a bore extending axially through the rotor 12 and the shaft 19 of the clutch mechanism 3 of the tool. The rod 50 is long enough to extend slightly beyond the upper end of the top rotor trunnion 50a of the tool motor and beyond the lower end of the clutch shaft 19 to reach and bear against the stem 33 of the adapter 34 within the spindle 32. An expansion spring 51 bears on the lever arm 49 to hold the push rod 50 against the adapter stem 33 as shown in Fig. 1.

The tool so far described and shown in Fig. 1 operates as follows: I have reference hereto to the opening of the sleeve valve 11 by the push rod 50. The rest of the parts operate in the

5 manner of a rotary impact tool of the character shown, the throttle valve 7 being the starting and stopping valve of the tool.

In the normal position of the parts, the adapter 34 is held in its outwardly extended position by the action of the springs 42 and 51 on the push rod 50. On applying the tool to the work, that is, on applying the socket member 37 over the nut or bolt to be driven and pressing downwardly on the tool through its side handle 4, the adapter member 34 is forced upwardly into the spindle 32 raising the rod 50 and opening the valve 11 through the lever 47. This opens the valve 11 wide enough to give the added air volume required to immediately pick up the load impressed on the tool. The nut or bolt seats the socket 37 and accounts for the relatively sliding movement between the adapter and the spindle on pressing the tool 20 against the work. The bolt is marked 52 in Fig. 1.

On removing the tool from the nut or bolt, the adapter 34 moves outwardly by gravity and spring action and the valve 11 closes. The tool 25 motor 2 idles at this time due to a small port 53 in the valve 11 being in register with the inlet ports 43 and 45 to supply a small amount of air to the tool motor to keep it idling at a relatively slow speed. The rotation of the tool 30 motor is completely stopped and started by the throttle valve 7.

In the embodiment of my invention shown in Fig. 2, the inlet valve is located in alignment with its actuating push rod thereby avoiding the need for the lever 47 in Fig. 1 and the expense and space incident thereto.

In Fig. 2, the inlet valve is marked 11a and is slidably mounted in a sleeve-like fixture 54 mounted in the upper end portion of the tool case 55 directly above and in axial alignment with the axis of the tool motor 2a which is of the rotary type as shown in Fig. 1. The valve 11a is in the form of an annular member having a peripheral flange 56 to open and close ports 57, 58 at opposite sides of the valve housing 54 and respectively connecting with passages 59, 60 in the tool case. The passage 59 leads to the main supply passage 9a in like manner as shown in Fig. 1.

The valve member 11a is provided with a depending stem 61 which slidably extends into a bore in the upper trunnion 62 of the tool motor 2a as shown. This bore extends axially through the rotor of the motor and also through the 55 clutch shaft in the same manner as shown in Fig. 1.

The spindle 32a of the clutch in Fig. 2 is journalled in the tool case and is hollow to receive the upper stem portion 63 of an adapter 64. The stem portion 63 has a non-rotative connection with the spindle 32a and is fixed against endwise or sliding movement therein by an interfitting groove and ring arrangement as shown at 65 in Fig. 2.

The lower square portion 66 of the adapter 64 extends below the spindle and mounts a nut or bolt engaging socket member 67 which has limited sliding movement on the adapter portion 66 and is retained in connected relation therewith by a detent pin 68 on the adapter extending into an axially elongated slot 69 in the socket member 67.

The lower stem portion 66 which mounts the socket 67 has a cross-slot 70 through which extends a cross-pin 71. The pin 71 extends at

its ends beyond the adapter stem 66 and mounts thereon a ring member 72. The latter bears on the upper end of the socket member 67 and is lifted therewith when the socket is applied to the work and the tool device is pressed downwardly against the work. The lower end of the actuating rod 73 engages the cross-pin 71 in the slot 70 which is elongated axially of the tool so that the socket member 67 in bearing on the engaged nut or bolt lifts the socket when pressed against the work.

The push rod 73 extends to and engages the valve stem 61 so that the upward movement of the rod in pushing down on the tool will lift the valve member 11a to open the ports 51, 58 to supply the increased volume of live air to the tool motor 2a to pick up the load. An expansion spring 74 in the valve housing 54 above the valve member 11a normally moves the valve member towards its closed position and maintains the rod 73 against the cross-pin 71. The valve flange 56 has an outside groove 75 in register with the ports 51, 58 to supply a limited amount of live air to the tool motor to keep it idling when the valve 11a is closed and the throttle valve is open. The upper end of the valve housing 54 is closed by a screw-cap 76 to adjust the tension of the valve spring 74 and to retain it in place.

The passage 60 in the tool case 55 leads to a port 77 which connects with the passage system of the tool for furnishing compressed air to the tool motor. The opposite sides of the impact elements 26 and of the anvil jaws 31 are provided with impact delivering and receiving surfaces, respectively, so that the clutch will function on rotating of the tool motor in opposite directions.

I may remark in passing that the clutch mechanism 3 within the tool serves to connect the tool motor through the hammer member 18 of the clutch to the anvil member 30 when the nut or bolt 52 is free to be driven. When the nut or bolt is not free to turn easily, as when tight, the torque of the tool motor is resisted and the clutch functions to impart a series of rotational hammer blows through the impacts of the dogs 26 against the sides of the jaws 31 to further tighten or loosen the nut or bolt as the case may be.

Regardless of the form of the impact clutch mechanism with which the tool is equipped, the push rod and valve arrangement disclosed herein provides for the opening of the valve to admit a larger volume of live air to the tool motor to rotate it in accordance with the load placed thereon on applying the tool to the work whether for a nut or bolt tightening or an unscrewing operation.

The arrangement disclosed is simple and inexpensive in construction and efficiently performs the function for which it is designed. Moreover the arrangement disclosed provides a compact tool construction for ease in handling and manipulation.

I claim as my invention:

1. In a portable power operated impact wrench, a fluid actuated rotary motor, a rotatable spindle driven by said motor, axially shiftable socket means operatively connected with said spindle for engaging a nut to be turned, manually operable means for supplying motive fluid to the motor, an inlet valve for controlling the admission of motive fluid to the motor, said inlet valve comprising a one-piece shiftable valve member and spring means normally urging said valve member to closed position, said valve member

5 being formed with by-pass porting means for admitting a limited supply of motive fluid to the motor when the valve member is in closed position whereby to permit said motor to operate at idling speed for facilitating engagement of said socket means with the nut to be turned while said socket means is rotating at a relatively low speed, an elongated valve-actuating member extending through said spindle and said motor in axially slidable relation therewith and operatively connected at one end thereof with said socket means, and means operatively connecting the opposite end of said valve actuating member with said valve member to effect opening of said inlet valve whereby to admit an increased supply of motive fluid to the motor for operating the latter at a relatively high nut-driving speed, said valve-actuating member being axially slidable into valve-opening position in response to movement of the wrench and the socket means axially against the nut to be turned.

2. In a portable power operated impact wrench, a fluid actuated rotary motor, a rotatable spindle driven by said motor, axially shiftable socket means operatively connected with said spindle for engaging a nut to be turned, manually operable means for supplying motive fluid to the motor, an inlet valve for controlling the admission of motive fluid to the motor, said inlet valve comprising a one-piece shiftable valve member and spring means normally urging said valve member to closed position, said valve member being formed with by-pass porting means for admitting a limited supply of motive fluid to the motor when the valve member is in closed position whereby to permit said motor to operate at idling speed for facilitating engagement of said socket means with the nut to be turned while said socket means is rotating at a relatively low speed, and an elongated rod extending through said spindle and said motor in axially slidable relation therewith and in substantial alignment with said valve member, said rod being operatively connected at one end thereof with said socket means and being directly engageable at its opposite end with said valve member for opening said inlet valve whereby to admit an increased supply of motive fluid to the motor for operating the latter at relatively high nut-driving speeds, said rod being axially slidable into valve-opening position in response to movement of the wrench and the socket means axially against the nut to be turned.

3. In a portable power operated impact wrench, a fluid actuated rotary motor, a rotatable spindle driven by said motor, axially shiftable socket means operatively connected with said spindle for engaging a nut to be turned, manually operable means for supplying motive fluid to the motor, an inlet valve for controlling the admission of motive fluid to the motor, said inlet valve comprising a one-piece shiftable valve member and spring means normally urging said valve member to closed position, said valve member being formed with by-pass porting means for admitting a limited supply of motive fluid to the motor when the valve member is in closed position whereby to permit said motor to operate at idling speed for facilitating engagement of said socket means with the nut to be turned while said socket means is rotating at a relatively low speed, an elongated rod extending through said spindle and said motor in axially slidable relation therewith and operatively connected at one end thereof with said socket means, said inlet valve being

disposed in laterally offset relation with respect to the axis of said rod, and pivotally supported lever means coacting between said valve member and the opposite end of said rod for effecting opening of said inlet valve whereby to admit an increased supply of motive fluid to the motor for operating the latter at a relatively high nut-driving speed, said lever means being rockable into valve-opening position upon axial sliding movement of said rod in response to movement of the wrench and the socket means axially against the nut to be turned.
